UNITED STATES PATENT OFFICE.

HARRY W. HUNTER, OF BALTIMORE, MARYLAND, ASSIGNOR, BY MESNE ASSIGNMENTS, TO UNION TRUST COMPANY OF MARYLAND, TRUSTEE, OF BALTIMORE, MARYLAND, A CORPORATION OF MARYLAND.

GAS RANGE.

Application filed January 5, 1922. Serial No. 527,141.

To all whom it may concern:

Be it known that I, HARRY W. HUNTER, a citizen of the United States, residing at Baltimore, in the county of Baltimore City 5 and State of Maryland, have invented a new and useful Gas Range, of which the following is a specification.

This invention is an attachment by means of which a thermostatic gas control may be 10 applied to a standard gas range.

One of the objects of the invention is to provide a gas range of standard construction provided with an oven burner, and simple means whereby a thermostatic control valve may be interposed between the 15 same and the gas manifold. A further object is to provide a gas range with the manifold so arranged that the thermostatic control device may be connected thereto without 20 in any manner altering the oven structure to which it is applied.

The invention will be hereinafter fully set forth and particularly pointed out in the claims.

25 In the accompanying drawing:-

Figure 1 is a plan view, illustrating more or less diagrammatically, a gas oven constructed in accordance with the invention. Figure 2 is an end view illustrating the invention without the thermostatic attachment. Figure 3 is a similar view illustrating the thermostatic attachment in position. Figure 4 is a detail view illustrating the thermostatic control device.

35 Referring to the drawing, 10 designates the oven of a standard gas range, and 11 the usual open cooking top. The gas manifold is provided with a section 12 leading across the front of the cooking top 11, to 40 supply the burners for the latter. Extending rearwardly from the section 12, beneath the cooking top 11, is a section 13, which is connected at the back of the range, with an inclined section 14, leading to a section 45 15 extending toward the front of the range, near the top of the oven.

The oven burner 16, which may be of any standard construction, extends into the oven through an opening 17, in the oven wall, and is maintained in its proper position by the aid of a collar 18. In Figure 2, said burner is shown as connected to the section 15 of the manifold, by a pipe or conduit member 19, and an interposed cock 20. Said cock con-

trols the flow of gas to the burner and is of 55 standard construction. The pipe 19 is provided with a section 27 steadied in position by a detachable clamp 21, secured to the oven wall in any desired manner.

Located directly above the hole 17, and 60 in alignment with the section 15 of the manifold, is an opening 22, normally closed by a cover plate, as shown in Figure 2.

In the form of the invention thus far described, the oven burner is lighted by means 65 of a pilot burner, in the usual way, by a flame introduced through the opening 17, the flow of gas being controlled by the cock 20.

When it is desired to apply a thermostatic 70 control for the burner 16, the section 27 is disconnected from the burner, and the pipe 19 is disconnected at the cock 20. The cover plate is also removed from the hole 75 22. The attachment illustrated in Figures 3 and 4 is then substituted for the parts so removed.

Referring to Figure 3, 25 designates the valve casing of the thermostatic control 80 member, which is connected by a pipe 26, with the cock 20, and by a pipe 27^a with 85 the burner. These elements constitute a unitary conduit member. A small pipe 28 leads from the pipe 26 to the pilot burner in a well-known manner. It will be observed that the pipe 27 is engaged by the 90 clamp 21.

In operation, the cock 20 is turned on full and the oven burner 16 is lighted 95 through the oven or broiler door. The pilot burner is lighted from the oven burner, and thereafter remains lighted as long as gas is permitted to flow through the cock 20. The flow of gas to burner 16 is automatically 100 controlled by the thermostat, and the pilot burner serves to relight the oven burner if the thermostat should cut off the flow of gas to said burner 16 at any time, and then subsequently operate to again permit flow of gas to the burner. The pilot burner therefore serves as a safety factor, in a well-known manner.

Any desired form of thermostatic control is within the purview of the invention. Excellent results have been obtained with the 105 device shown in Figure 4 for illustrative purposes only, and no claim is made therefor,

- Referring to Figure 4, 25 designates the valve casing, which is provided with a gas inlet opening 29 connected with pipe 26, and an outlet opening communicating with pipe 25. Flow of gas through the casing is controlled by a disk-like valve 30, normally pressed to its seat by a spring 31. The expansible element of the thermostat consists of a metal tube 32, adjustably connected at one end with a nipple 33, of the casing 25, by means of a threaded sleeve 34. The other end of the tube 32 is closed by a plug 35, against which bears one end of a rod 36, the other end of which abuts against a stem 37, formed on the valve disk 30. A handle 38 is secured to the sleeve 34, to adjust the position of the tube 32 with respect to the casing 25, so that the device may be set to shut off the gas at different temperatures. It is preferred to provide the handle 38 with a pointer 39, mounted to travel over a temperature scale 40. It will be readily understood from Figure 3, that the tube 32 and its enclosed elements, are inserted into the oven, through the hole 22, in a position where they will be exposed to the heat of the burner, the opening being substantially closed by the casing 25.
- The advantages of the invention will be apparent to those skilled in the art to which it belongs. By directing the manifold around the back of the oven, and inserting the burner into the oven through the end, instead of through the front, which is the standard practice, it is possible to provide a gas range which will perform all of the normal functions of stoves of this type, and the customer is not required to accept the thermostatic control, with the added expense, if he does not desire to do so. On the other hand, if the thermostatic control is desired, it may be applied at any time, with little or no trouble, and without in any manner altering or injuring the stove structure.
- Having thus explained the nature of the invention and described an operative manner of constructing and using the same, although without attempting to set forth all of the forms in which it may be made, or all of the forms of its use, what is claimed is:—
1. The combination with a gas range provided with an oven and having a normally closed opening in one end wall of the oven adapted to receive a thermostatic device, of a gas manifold terminating in a short branch overlapping said oven end wall, a burner extending into the oven through said end wall, and a removable conduit member consisting of two angularly disposed portions lying in a plane parallel with said end wall, one of said portions being connected to the burner and the other with said manifold branch, and a joint between the portions of said conduit member located opposite said opening, whereby a similar conduit member having a thermostatic device located at said joint and extending into the oven may be readily substituted for the first mentioned conduit member.
2. The combination with a gas range provided with an oven and having a normally closed opening in one end wall of the oven adapted to receive a thermostatic device, of a gas manifold extending back of the oven and terminating in a short forwardly extended branch overlapping said oven end wall, a burner extending into the oven through said end wall, and a removable conduit member consisting of two angularly disposed portions lying in a plane parallel with said end wall, one of said portions being connected to the burner and the other with said manifold branch, and a joint between the portions of said conduit member being located opposite said opening, whereby a similar conduit member having a thermostatic device located at said joint and extending into the oven may be readily substituted for the first mentioned conduit member, and a cock interposed between said manifold branch and the contiguous angularly disposed portions of the conduit member.
3. The combination with a gas range provided with an oven, of a gas manifold extending back of the oven and terminating in a short forwardly projecting branch overlapping one end wall of said oven, a burner extended into the oven through said end wall, and a removable thermostatic member consisting of two angularly disposed conduit members one of which is connected to the burner and the other with the forwardly projected overlapping manifold branch, and a thermostatic control device supported by said angularly disposed conduit members at the intersection thereof and extending into the oven.
4. The combination with a gas range provided with an oven, of a gas manifold extending back of the oven and terminating in a short forwardly projecting branch overlapping one end wall of said oven, a burner extended into the oven through said end wall, a removable thermostatic member consisting of two angularly disposed conduit members one of which is connected to the burner and the other with the forwardly projected overlapping manifold branch, a thermostatic control device supported by said angularly disposed conduit members at the intersection thereof and extending into the oven, and a cock interposed between said forwardly projecting branch and the contiguous element of the two angularly disposed conduit members.
- In testimony whereof I have hereunto set my hand.

HARRY W. HUNTER.
